UNITED STATES PATENT OFFICE.

JOHN G. JONES, OF ROCHESTER, NEW YORK, ASSIGNOR TO EASTMAN KODAK COMPANY, OF ROCHESTER, NEW YORK, A CORPORATION OF NEW YORK.

PACKAGE OF X-RAY FILMS.

1,395,918.

Specification of Letters Patent.

Patented Nov. 1, 1921.

Application filed August 27, 1919. Serial No. 320,283.

To all whom it may concern:

Be it known that I, JOHN G. JONES, citizen of the United States of America, residing at Rochester, in the county of Monroe and State of New York, have invented certain new and useful Improvements in Packages of X-Ray Films, of which the following is a full, clear, and exact specification.

This invention relates to a package of X-ray film in which the individual films come separately packed in light-proof packages and upon which X-ray exposures are made, the package not being opened until after the exposure is completed. This application is, 15 as to all common subject matter, a continuation in part of my application, Serial No. 276,637, filed Feb. 12, 1919.

It relates more particularly to such a package in which is placed a sheet of foil of heavy 20 metal such as tin or lead which is placed in back of the film and the edges of which are interfolded with the edges of a piece of protective wrapping paper, the intercrimped edges constituting a light-tight stiffening 25 bead around the edge of the package. This bead is so constructed that it may be partially opened to admit fluid but still be light-tight. The package particularly described is intended for use in dental work but the 30 advantages of my invention are not limited to such use. Other advantages will be evident from a perusal of the specification and inspection of the accompanying drawings in which:

Figure 1 is a perspective view of the package;

Fig. 2 shows in perspective the separated component parts thereof;

Fig. 3 is a sectional view of the package in 40 process of manufacture and held in suitable dies;

Fig. 4 is a sectional view of the package and dies at another stage of the process;

Figs. 5 and 6 are sections of the uncompleted package in different stages;

Fig. 7 is a section of the finished package;

Fig. 8 is a section of the package with one element removed preparatory to opening the package;

50 Fig. 9 is a section showing the package partially opened;

Fig. 10 is a section of an alternative form of package;

Fig. 11 shows the same partially opened;

Fig. 12 is a section of another alternative form; and

Fig. 13 shows the same partially opened.

Fig. 14 is a section of still another form, and

Fig. 15 shows the same partially opened. 60

The same reference characters indicate the same parts in the different figures of the drawing. The preferred form of my package is shown in Figs. 1 to 9. This package consists of the following elements shown in 65 Fig. 2: Two sheets of sensitized film 2 lying between sheets of protective paper 10 which may be water-proofed, an inclosing envelop of paper 4 having a continuous flanged edge 7 and a sheet of metallic foil 3 having a 70 flanged edge 5 and a sheet of paper 11. These elements are here shown in a convenient way so that their relative location may be readily and easily perceived. It is to be understood, however, that this figure is 75 not intended to represent them as they are at any one time since the flange 7 may or may not be formed before any of the other elements are placed on sheet 4 and flange 7 is necessarily bent before sheet 11 is added as 80 will appear from the description hereinafter.

The sheets of sensitized film 2 are placed between the sheets of protective paper 10 and upon these is placed the sheet 3 of metal foil with the upturned flanges 5. These assembled elements are placed on the sheet 4 in an unfolded condition. These various elements are assembled with a die 14 fitting within the flange 5 and directly above the die member 15 having the aperture 16. Downward pressure is then exerted upon the die 14 forcing the assembled elements into the aperture at 16 whereupon the flange 7 is formed around the edges of the paper 4 as shown in Fig. 4. 90

In a separate operation the upper edges of the flange 7 are bent over the flanges 5 as indicated at 8, Fig. 5, and upon these overturned flanges is placed the sheet of paper 11 which may contain any desired printed matter. This sheet 11 is now forced 95 by any suitable die down within the flanges completing the bending of flange 8. The sheet 11 fits snugly within the overturned flange. At this stage it is not pushed completely home but remains out of contact 100 with foil 3 as indicated in Fig. 6. In another operation the combined flanges 5 and 7 are turned over upon the sheet 11 which is 105

2
at the same time pushed down tightly into contact with the foil 5, as shown in Fig. 7. The sheet of paper 11 has the function of insuring that the fold 8 of the flange 7 cannot 5 not become loose or unfolded after the package is bent or submitted to rough usage. The bottom portion 9 of the flange 8 will be securely caught around the edge of the paper 11; the flange 5 will be bent over into the 10 overhanging flange 6 while the flange 7 will be bent over at 12. There is thus provided a bead 13 around the edge of the package which is light-tight even under adverse conditions of usage and moreover fur- 15 nishes a strengthening bead which causes the package to hold its shape.

It is understood that while I have described one method of manufacture the flange 7 may be formed about the sheet 4 20 and the elements placed therein either singly or as an assemblage or any other desired or equivalent method of forming the package may be used.

An added advantage obtained by the 25 structure herein disclosed is that the package may be partially opened so as to afford ready access to fluids for developing purposes. The operator may, therefore, after exposure of the film readily unfold the 30 package with his fingers along one edge and drop it into a tank of developer. To accomplish this purpose the piece of paper 11 is first crumpled or pinched by the fingers and its edges thus drawn from under the 35 overhanging flange 8 leaving the package in the condition shown in Fig. 8. The bead around part of the package is then straightened up with the finger nail and the tightly folded elem. its somewhat loosened, thus 40 permitting the access of fluid to the interior of the package and the sensitized film. This may be assisted by gently pressing the edges of the package, permitting or causing the elements thereof to become slightly sepa- 45 rated. The package would appear some- what as shown in Fig. 9. It is to be noted that this light trapped but fluid admitting entrance can be made because of the double folding or crimping together of the edges 50 of the foil and the paper and would be im- possible if only a single layer of material were pressed down around the edge. The package thus partially opened is dropped into a tank of developing fluid which may 55 then be covered. This fluid develops the image in the sensitive film and it also softens the paper which loses its stiffness and the joint no longer holds the edge together so that the package normally falls apart. If 60 the developing tank is of the common type, into which the fluids can be poured and from which they can be drawn by means of suitable tubes, stop-cocks, etc., the process becomes entirely a daylight one. The various 65 pieces of paper referred to are impervious

to actinic light rays but pervious to X-rays. They may or may not be waterproofed. As indicated in certain alternative forms hereinafter described the protecting layers 10 may be entirely omitted as may the sheet 11 70 and only one sheet of sensitized film need be used. If this is done it would be preferably sensitized upon both surfaces. If the sheets 10 are water-proofed upon one side only it would be upon that side far- 75thest removed from the films and if the films 2 are sensitized upon one side only it would be upon that side farthest from the foil. The purpose of the additional protective sheets is to avoid any possibility of 80 light entering through pin holes which might occur in the outer coverings.

If desired, the protective sheets 10 may be of highly absorbent material such as blotting paper in order to insure that the fluid 85 admitted to the package along one edge will reach the entire surface of the film. If made of this material the sensitized surface would be placed on that side of the film which would contact these protective papers. 90 If these absorbent papers are used, it would be possible to punch notches at selected points in the edges of the package. The package would then in an unopened condition be dropped into a tank of developer 95 and the fluid having access to the absorbent material would permeate throughout it and reach the sensitized surface throughout its entire area. At the most this could not fog more than a very slight extent imme- 100 diately around the notch and would not affect the recorded image since the notches would be made at the points where fogging would do the least damage.

Fig. 10 illustrates a form in which only 105 one sheet of sensitized film 2 is used and the protective paper is omitted. Sheet 11 is also omitted, the package consisting only of the sheet of foil 3, the film 2 and the outer paper 4. However, an interlocking bead is 110 formed, the flange 7 being bent at 12 and bent again to form the overhanging flange 8 around the parts 6 and 5. On account of the double bending of the flange 7 it may be opened as shown in Fig. 11 to form the 115 light tight but fluid admitting entrance of the package. Fig. 12 shows another modified form of package similar in every way to the preferred form except that the paper 11 is omitted. As shown in Fig. 13, it may 120 be partially opened to admit fluid but not light.

In the form shown in Fig. 14 the metal foil 3' is made with a flange 5' which is longer than the flange 7' of the paper 4' 125 and this metallic flange is bent around the film and around the paper flange to form the strengthening bead on that side of the film which is opposite to the sheet of foil. The flange may also be opened as shown in Fig. 130

15 to form an entrance for fluid but not light. This form, however, is not preferred as the overlapping flange of the foil cuts down the possible exposure area of the film,
5 and in dental work where the film must be thrust well up behind the roots of the teeth, the slightest fraction of an inch at these points is of great value. The arrows in the various figures indicate the direction in which the
10 X-ray will fall upon the film and it will be evident that in Figs. 7, 10 and 12, the entire surface of the film will be open to exposure to the X-rays while the advantages gained by use of foil are also attained. These advantages in such packages are that secondary radiation is prevented, the package is given a greater stiffness and the inter-crimping of the foil and paper secures without the use of paste or glue, a tight package. When
15 the foil is submitted to pressure it fills up cracks and interstices of the bead of which it is a part. In several of the figures the different component parts are shown separated but this is merely for purposes of illustration so that the drawings will not be confused except for the space in Fig. 6 between the elements 11 and 3 and the spacing between the elements in the partially opened packages.
20 50 It should be understood that except as limited by the claims, the embodiments here described are to be taken as illustrative only, and that I contemplate as within the scope of my invention the use of equivalent elements and steps in manufacture.

Having thus described my invention, what I claim as new and desire to secure by Letters Patent is:

1. A package comprising at least three
40 sheets of material lying in parallel planes, including one sheet of sensitized film, one sheet of protective paper and one sheet of metal foil, the edges of the sheets of paper and foil being interfolded.

45 2. A package comprising at least one sheet of sensitized film, at least one sheet of protective paper and at least one sheet of metal foil, the edges of the paper and foil being interfolded, the sheets being plane and parallel and the foil lying entirely upon one side only of the film.

50 55 3. As an article of manufacture, a package comprising a sheet of sensitized film, a sheet of metal foil of greater dimensions than the film and covering one side of the film, a sheet of flexible material impervious to actinic light rays and pervious to X-rays and of greater dimensions than the film and covering the other side of the film, the edges of the foil and flexible material being folded together upon a face of the package thus formed to make a strengthening, light-tight edge.

60 65 4. A package comprising a sheet of sensitized film, a sheet of metal foil of greater

dimensions than the film and covering one side of the film, a sheet of flexible material impervious to actinic light rays and pervious to X-rays and of greater dimensions than the film and covering the other side of the film, the edges of the foil and flexible material being folded together upon that face of the package that is adjacent to the foil to form a strengthening, light-tight edge, whereby the whole area of the film is open to exposure to X-rays.

5. A package comprising a sheet of sensitized film, a sheet of metal foil lying upon one side of the film, a sheet of flexible material impervious to light rays and pervious to X-rays and covering the other side of the film, a sheet of material lying upon the foil, the edges of the foil and the flexible material being folded together over the surface of the last named sheet which fits tightly within said folded edge whereby a tightly locked strengthening bead is formed around the edge of the package.

6. A package of X-ray dental film comprising a sheet of paper opaque to light rays and pervious to X-rays, a sheet of waterproof paper thereon, at least one sheet of sensitized film thereon, a sheet of waterproof paper on the film, a sheet of metal foil on the last named sheet of paper, and a sheet of paper on the foil, the edges of the foil and the first named paper being folded together over the surface of the last named paper, which fits tightly within said folded edge, whereby a tightly locked strengthening bead is formed around the edge of the package, the whole area of the film being covered on one side by paper only.

7. A package comprising a sheet of sensitized film, a sheet of metal foil and a sheet of opaque paper placed one on each side of said film, the edges thereof being interfolded together on one face of the package thus formed, one of said last named sheets being folded at least twice in the interfolding mentioned whereby the fold may be partially opened to admit fluid while being still light tight.

8. A package comprising a sheet of sensitized material, a sheet of metal foil of greater dimensions than said first named sheet and covering one side thereof, a sheet of flexible material impervious to actinic light rays and pervious to X-rays and of greater dimensions than the first named sheet, and covering the other side thereof, the edges of the foil and flexible material being folded together, so that one of them is bent at least twice in the formation of the fold, whereby the fold may be loosely opened to permit access of fluid to the package, while barring the entrance of light.

9. A package comprising a sheet of sensitized material, sheets of foldable material one on each side of said sensitized sheet, the

edges of the last named sheets being inter-folded together on one face of the package thus formed, one of said last named sheets being folded at least twice in the inter-
5 folding.

10. A package of X-ray dental film comprising a sheet of sensitized material and sheets of bendable material of greater dimension than said first named sheet covering each face thereof, the edges of said last named sheets being folded together into a stiffening bead overlying one surface of the sensitized sheet and extending around the entire periphery of the package.

15. 11. The method of making a package of sensitized film which comprises: first, assembling the following three elements, a flanged sheet of metallic foil, a sheet of sensitized film, and a sheet of paper having a flange 20 fitting around the other two elements; second, bending the paper flange over the metal flange; third, forcing another sheet of paper within the flanges, but not quite to the bottom thereof, and in the same operation, completing the folding of the paper flange over the metal flange; and fourth, bending said metal and paper flanges down tightly upon said inserted paper sheet, thus pressing it down into contact with the foil and forming 25 a tightly locked joint around the edge of the package.

12. The method of making a package of sensitized film which comprises: first, assembling the following three elements, a sheet 30 of flexible material with a continuous flange around the edge thereof, a sheet of sensi-

tized film fitting within said flange, and a sheet of metal foil with a continuous flange around the edge thereof of less height than the first named flange and fitting snugly 40 therein; second, bending the first named flange over the metal flange; third, forcing a second sheet of flexible material within but not to the bottom of the flanges, thereby completing the bending of the first named flange around the metal flange; and fourth, bending said combined flanges down tightly upon said inserted sheet, thus pressing it down into contact with the foil and forming 45 a tightly locked joint around the edge 50 of the package.

13. The method of making a package of sensitized film which comprises: first, assembling the following elements, a flanged sheet of bendable material, a sheet of sensitized film, and a sheet of paper having a flange fitting around the other two elements; second, bending the second flange over the first; third, forcing another sheet of paper within the flanges, but not quite to the bottom thereof, and in the same operation, completing the folding of the second flange over the first; and fourth, bending said two flanges down tightly upon said inserted paper sheet, thus pressing it down into contact with the sheet of bendable material and forming a tightly locked joint around the 60 edge of the package.

Signed at Rochester, New York, this 22nd day of August 1919.

JOHN G. JONES.
